DESIGN FOR A LAMP

Lawrence Rosenfeld, New York, N. Y.

Application February 18, 1936, Serial No. 61,219

Term of patent 3½ years

To all whom it may concern:

Be it known that I, Lawrence Rosenfeld, a citizen of the United States of America, residing in Manhattan, county of New York, and State of New York, have invented a new, original, and ornamental Design for a Lamp, of which the following is a specification, reference being had to the accompanying drawing, forming part thereof, wherein,

Figure 1 is a plan perspective view of a lamp showing my new design.

Figure 2 is an elevational view of the lamp shown in Figure 1.

The shaded circular area resting on the cross-piece shade support, as shown in Figure 1, represents a translucent disc.

The opposite sides of the lamp herein shown are substantially the same in appearance.

I claim:

The ornamental design for a lamp, substantially as shown and described.

LAWRENCE ROSENFELD.
